UNITED STATES PATENT OFFICE.

LLOYD D. COLLAR, OF YREKA, CALIFORNIA.

OIL-BURNING SYSTEM.

1,110,745.

specification of Letters Patent. Patented Sept. 15, 1914.

Application filed February 25, 1914. Serial No. 820,859.

To all whom it may concern:

Be it known that I, LLOYD D. COLLAR, a citizen of the United States, residing at Yreka, in the county of Siskiyou and State 5 of California, have invented new and useful Improvements in Oil-Burning Systems, of which the following is a specification.

This invention relates to improvements in oil burning systems.

10 It is one of the objects of the present invention to provide a simple, substantial, easily operated oil burning system which is so constructed that it may be applied to furnaces ranging in size from large units down 15 to small cooking stoves.

Another object is to provide means for generating steam as it is needed for heating and atomizing the oil. A further object is to provide means for feeding and straining 20 the oil.

The invention consists of the parts and the construction and combination of parts as hereinafter more fully described and claimed, having reference to the accompanying drawing, in which the figure is a dia- 25 grammatic view of the system showing the different parts connected.

Referring to the drawings, A indicates a furnace box, 2 a suitable form of oil burner, 30 and 3 a curved baffle or deflecting plate, adjustably mounted in the path of the flames through the medium of a lever 4. Suitably secured within the furnace box is a steam generating coil 5. One side of this coil is 35 connected through a pipe 6 with a source of water supply under pressure, indicated at 7. This may represent a water main.

A valve 8 is provided on line 6 to regulate the flow of water through the coil. The 40 other side of the coil is connected with the burner through a pipe 9, and a valve 10 is provided to regulate the steam flow to the burner.

11 indicates an oil tank. 12 a suitable form 45 of oil filter or strainer, and 13 an oil heater. The bottom of tank 11 is connected with the water main 7, and a valve 14 is inter- 50 posed on this connection. The top of the tank is connected with the oil strainer through a pipe 15, and this in turn is connected through a pipe 16 with the top of an oil heater 17. The oil heater is produced by providing the outer jacket 13, in which pipe 16 is coiled, as indicated at 18. Steam 55 is admitted to the jacket 13 through a branch connection 19, and the steam flow

through same is regulated by a valve 20. The oil, after being thoroughly heated, is then conveyed to the burner through a pipe 21, and a valve 22 is provided at the burner 60 to regulate the flow of same. The filter or strainer shown consists of an outer jacket 12, the upper end of which is connected with the oil tank, while the lower end is connected with the oil heater. Interposed be- 65 tween the inlet and outlet openings is a suitable form of screen 23, or other medium, through which the oil is forced before escaping through the pipe 16.

The deflecting plate shown in the furnace 70 is provided partly for the purpose of deflecting the flames from the coil heater, indicated at 5, and is also provided to reverse the path of the flames for the purpose of creating better combustion and consuming 75 any smoke that might otherwise escape.

In operation, it is only necessary to start a temporary fire under coil 5. Valve 8 is then opened to admit water, and valve 20 is also opened to permit the steam to pass 80 through the heater 13 to heat the oil. Valve 14, being opened, will permit the water to enter below the oil and force it out through pipe 15, through strainer 12 and through the coil 18 of the heater. The moment suf- 85 ficient steam has been generated and the temperature of the oil has become sufficiently high, it will only be necessary to open valves 10 and 22. The atomized oil ejected from the burner 2 will then instantly become ig- 90 nited by the temporary fire built within the furnace and the heat from the burner will then generate steam in a sufficient quantity to operate the system.

An oil burning system constructed as here 95 shown may be very cheaply and easily installed in furnaces ranging in size from large units down to small cooking stoves. The size of the coil 5 is increased or de- 100 creased according to the size of the burner and the furnace box. The connection with a source of water supply under pressure, as the water main 7, eliminates the use of any oil pumps, feed pumps or injectors. The provision of the several valves on the differ- 105 ent pipe connections permit a nicety of adjustment, which, together with the arrangement and connection of the different parts of the system, produces ideal results. The materials and finish of the several parts of 110 the system are such as the experience and judgment of the manufacturer may dictate.

Having thus described my invention, what I claim and desire to secure by Letters Patent is—

1. In an oil burning system, a furnace 5 having an oil burner therein, an oil tank, an oil heater interposed between the oil tank and burner and being located in spaced relation to the tank and independent of the latter and closely adjacent to the burner, a 10 connection leading from the tank and having a coiled part in the heater and connected to the burner, a steam generating coil in the furnace, common means to supply water under pressure to the oil tank at the 15 base of the latter to raise the oil and to supply water to said steam generating coil, and common means connected to the coil to both supply steam to the burner and to the heater.
2. In an oil burning system, a furnace 20 having an oil burner and a steam generating coil therein, an oil tank, an oil heater interposed between the tank and burner, and connected to each and being located in spaced relation to the tank and independent

of the latter, a connection between the steam 25 generating coil and the burner, and a connection between the oil heater and said first named connection to supply steam to the oil heater.

3. In an oil burning system, a furnace 30 having an oil burner and a steam generating coil therein, an oil tank, an oil heater located exteriorly of the tank and being independent of the tank and communicating with the latter and with the burner, a connection between the steam generating coil and the burner, and means to both feed water to the steam generating coil and to feed water under pressure to the oil tank at the base of the latter to raise the oil in 40 the tank to feed the oil to the heater.

In testimony whereof I have hereunto set my hand in the presence of two subscribing witnesses.

LLOYD D. COLLAR.
